CLAIM

The ornamental design for a dispensing container and cover, as shown and described.

DESCRIPTION

FIG. 1 is a right side elevation view of a dispensing container and cover showing my new design;
 FIG. 2 is a rear view thereof;
 FIG. 3 is a front view thereof;
 FIG. 4 is a right side view thereof, with the cover shown closed;
 FIG. 5 is a top plan view thereof, with the cover shown closed;
 FIG. 6 is a bottom plan view thereof, with the cover shown closed;
 FIG. 7 is a top plan view thereof, with the cover shown open;
 FIG. 8 is a right side elevation view of a second alternate embodiment, the only difference residing in the height of the container; and,
 FIG. 9 is a front perspective view of FIG. 8.
